(57) **CLAIM**

The ornamental design for a pet door as shown and described.

DESCRIPTION

FIG. 1 is a left view of a pet door showing my new design; FIG. 2 is a top view thereof; FIG. 3 is a front view thereof; FIG. 4 is a bottom view thereof; FIG. 5 is a right view thereof; FIG. 6 is a rear view thereof; and, FIG. 7 is a perspective view thereof.

The broken lines in the figures illustrate portions of the pet door that form no part of the claimed design.
